GRAIN GRINDER GATE VALVE

Howard M. Johnston, Toronto, Ontario, Canada,
assignor to Massey-Harris Company Ltd.,
Toronto, Ontario, Canada, a limited company
of Canada

Application February 6, 1941, Serial No. 377,622

1 Claim. (Cl. 83—8)

My invention relates to grain grinders and means for feeding the grain and regulating its flow into the grinding plates.

An object of the present invention is to provide simple means for definitely regulating the flow of grain through the grinder which will not clog in any position of adjustment.

In grain grinders of the class, a non clog gate valve is not practical unless some agitating means is provided which will prevent the grain from bridging the adjusted feed opening. Such means are usually noisy and expensive.

I provide a gate valve which practically surrounds a reduced in diameter portion of the spiral feeding mechanism so a regulated or restricted opening is formed therearound thus to continuously agitate the grain as it approaches and passes through the opening.

My invention insures a uniform flow of grain through the mill thus to insure a uniformly ground product.

To these and other useful ends, my invention consists of parts, combinations of parts, or their equivalents, and mode of operation, as herein-after described and claimed and shown in the accompanying drawings in which:

Fig. 1 is a longitudinal vertical sectional view through the center of my device as applied to the preferred design of grinders.

Fig. 2 is an end sectional view taken on line 2—2 of Figure 1.

As thus illustrated, the base, or main frame of my grinder is designated in its entirety by reference character A and the rotating part of my invention is designated by reference character B.

Member A comprises a base member 8, and a pedestal 9 having a circular in cross section chamber 10, one end being open as at 11 and the other end being closed and having a boss 12 with a central aperture 13. A hopper 14 is preferably integrally formed with chamber 10 and pedestal 9, as illustrated.

Hopper 14 intersects chamber 10 as at 15. The other end of base A is provided with a pedestal 16 having an aperture 17. A shaft 18 is slidably mounted in apertures 13 and 17. Shaft 18 is concentric with chamber 10 and extends therethrough, as illustrated.

I provide a belt pulley 19 which is rotatably mounted on shaft 18 by means of ball or roller bearings 20—20 which are held in position by means of flanged end members 21 and 22. These bearings are mounted so as to prevent longitudinal movement of the pulley on the shaft, as illustrated.

Members 21 and 22 are provided with annular grooves 23—23 for the reception of suitable packing material. The inner hub members of the pulley are also provided with grooves 24—24 for the reception of packing material thus to inclose the bearings within oil tight chambers.

I provide an internally threaded annular flange 25 on the outer surface of member 22, the end being trued and the outer surface being adapted to support a grinder plate supporting disc 26, the inner part of the disc having lugs which are adapted to contact driving projections on members 22 or 25. The aperture in member 26 is slightly convexed as at 27 so the disc will be permitted to rock slightly and thus adjust itself dynamically after the pulley gets up to speed.

An annular grinding plate 28 is secured to member 26. A grinding plate 31 is mounted on the inner face of member 9 and is concentric with chamber 10. The face upon which member 31 is secured is made uniform and a housing 33 is secured to this face, the inner diameter of the housing being somewhat larger than plate 26.

Member 33 is preferably provided with an opening as at 34 which registers with an opening 35 in base 8 forming an outlet for the ground material. It will be seen that the longitudinal position of shaft 18 will determine the position of plate 28 relative to plate 31 for fine or coarse grinding.

Member 25 is provided with an internal thread 36 for the reception of the threaded end of a tube 37. The tube is provided with a flange 38 which is machine trued on its face so when member 37 is screw threaded into member 25, it will be caused to turn true with pulley 19. Flange 38 projects past the outer diameter of hub 25 so as to hold disc 26 into position.

I provide means (not shown) of which member 40 forms a part whereby shaft 17 may be moved longitudinally for adjusting the space between plates 28 and 31.

The opening in member 37 is made large enough so it will not contact shaft 18. The outer surface of member 37 is provided with fairly large in diameter spiral threads 41 on its rear end and preferably relatively small in diameter spiral threads 42 on its forward end within the outlet. These spirals are adapted to act as conveying means for the grain.

I provide means for regulating the flow of grain through the grinder or to the grinding plates as follows:

Members 41 terminate a short distance from

the front face 43 of hopper 14. I provide a gate valve 45 which fits against face 43 and is made about the same width as the diameter of chamber 10 (see Figure 2) the lower central portion being cut out as at 46 to a diameter which is slightly larger than the outside diameter of members 42, as indicated by dotted lines in Figure 2. Gate valve 45 extends upwardly in contact with face 43 terminating at its top in a right angle bend 47.

I provide a slot 48 in hopper 14 and secure a bolt 49 to member 45 which extends loosely through slot 48, the bolt having a nut 50. It will be seen that gate 45 may be moved and held in any desired position. Cut-away portion 46 is positioned relative to bolt 49 whereby when valve 45 is in its lowest position permitted by slot 48, the cut-away portion 46 will extend around members 42 and in close proximity thereto (see dotted lines in Figure 2).

In the design shown, when the valve is in its lowest position, a minimum amount of grain will be fed into the grinding plates. The flow of feed is increased as the gate is raised until it reaches the position shown in Figure 2. Clearly the desired change in flow of feed from the hopper to the grinding plates will be available.

Spirals 41 are designed so as to supply the grinding plates with the maximum amount of grain when the valve is in its highest position and when the valve is in its lowest position, a minimum amount of grain will be fed into the grinding plates.

It will be noted that there is no possibility of grain clogging regardless of where the valve is positioned because there will always be agitation under or adjacent the valve to insure a uniform flow of grain to the plates.

It will be seen that I have provided a very simple and efficient means for regulating the flow of grain from the hopper to the grinding plates.

In Figure 1, I have shown the hopper as diverging outwardly from a point as at 51. The

central portion of the hopper is left straight for contact with valve 45, as illustrated. The opening left between the diverging parts of the hopper is large enough to provide convenient access to nut 50. I have secured maximum hopper capacity and a convenient seat for the valve.

It will be understood that my invention may be applied to other grinder designs. For example, where the shaft is designed to rotate and to which the operating parts of the device are attached.

Clearly many minor detail changes may be made without departing from the spirit and scope of the present invention, as recited in the appended claim.

Having thus shown and described my invention, I claim:

A device of the class described, comprising a hopper having at its bottom a uniform for its length horizontally arranged generally circular 20 in cross section chamber, one end being open forming an outlet, a rotatably mounted member extending concentrically and longitudinally through said chamber, a grinding plate concentrically positioned with said chamber and partially contacting the forward end of said hopper, driving means operatively connected to said member and having another grinder plate mounted thereon and positioned adjacent said first plate, an auger conveyor mounted on said member and positioned in said chamber, the end protruding through said outlet, a portion of said auger conveyor from said protruding end to a short distance past the inside vertical plane of the hopper being somewhat smaller in diameter 30 than the remainder of the auger, a vertically arranged gate valve positioned on the inside of said hopper adjacent said outlet and being cut-away at its bottom so the valve, when closed, may partially surround said reduced portion of the auger leaving substantially the lower half of said outlet chamber and the reduced portion of the auger open for the passage of the material.

HOWARD M. JOHNSTON.
